TOY AIRPLANE

Alexander D. Geraci, Roselle, Ill.

Application December 11, 1958, Serial No. 53,736

Term of patent 14 years

(Cl. D34—15)

Fig. 1.

Fig. 2.

Fig. 3.

Fig 4.

Fig 5.

Figure 1 is a perspective view of a toy airplane showing my new design;

Figure 2 is a top plan view thereof;

Figure 3 is a side elevational view thereof;

Figure 4 is a front elevational view thereof; and

Figure 5 is a rear elevational view thereof.

I claim:

The ornamental design for a toy airplane, substantially as shown.
